UNITED STATES PATENT OFFICE.

CHARLES L. CURTIS, OF BROOKLYN, NEW YORK, ASSIGNOR TO THE N. B. ABBOTT MACHINE COMPANY, OF NEW YORK.

BOTTLE-WIRING MACHINE.

SPECIFICATION forming part of Letters Patent No. 448,854, dated March 24, 1891.

Application filed December 31, 1890. Serial No. 376,373. (No model.)

To all whom it may concern:

Be it known that I, CHARLES L. CURTIS, a citizen of the United States, residing in Brooklyn, Kings county, New York, have invented 5 certain Improvements in Bottle-Wiring Machines, of which the following is a specification.

My invention relates to the class of machines employed for applying the wire stopper-retainer to bottles and similar receptacles; and the object of the invention is to produce a comparatively simple machine adapted 10 to receive, hold, and wire the bottle automatically at one operation of the machine. 15 The wire retainer applied by my machine consists of a band about the bottle-neck below the fillet and branches which spring from said band extend up over the cork and are united by a single twist on the top of the latter. By 20 preference the band is of a single strand of wire, and the retainer is made up of three pieces of wire laid about the bottle-neck by the machine, and these twisted together to form three branches. By preference, also, 25 the strands of wire are united by a short twist, and the two untwisted strands are carried up over the cork, where the six strands are united by a single twist, which is trimmed off and the twist then flattened down on the 30 cork.

Before proceeding to describe the machine minutely with reference to the accompanying drawings, I will describe it generally with a view of imparting a better understanding of 35 the principles upon which it operates and the objects sought to be attained by the special construction thereof.

The machine is adapted for applying a wire retainer having three strands over the cork. 40 In the vertical axis of the machine below is rotatively mounted an automatic holder for the bottle adapted to clamp on and hold bottles of different dimensions within limits. When placed in the machine by the attendant, the bottle stands erect in the axis of the machine with its stoppered or corked end uppermost. Guide-fingers on the holder serve to guide the operator in placing the bottle. Arranged about the bottle-holder and equally 45 spaced are set three posts or uprights constituting parts of the machine-frame, and on

each of these posts is mounted a mechanism for feeding a wire from a wire holder or reel inward to and alongside the bottle-neck, a cutter to sever a piece from the wire, a twister to form 55 one of the three twists where the branches join the band, and a lifter to lift the pair of wires forming the branch into an upright position. The three mechanisms placed about the bottles are alike or may be alike. Each 60 has, as stated, a feeder which draws the wire from the reel or holder and projects it inward past the bottle-neck and parallel to a tangent thereto, the end of the wire entering between the jaws of the twister on the next 65 adjacent device. Thus when each device has fed its wire forward the bottle-neck will be embraced by three substantially straight strands of wire forming a triangle, and these strands will meet and cross each other at 70 three points, and these three points will be in the jaws of the respective twisters. The twister-jaws now close on the wires at these crossing points, and simultaneously each wire is cut off and the twisters move inward radially 75 toward the bottle-neck. The twisters now rotate axially, making, by preference, two complete revolutions. When the twists are made, the effect is to close the wires on the bottle-neck to form the band and to leave three 80 branches in the twisters. The jaws of the twisters now open and draw back and the lifters take under the three branches formed by the twists and lift them into an upright position. 85

Directly over the cork in the bottle and in the vertical axis of the machine is mounted a gripper-head, which is in the nature of a block with three vertically-arranged radial slots so set as to receive the three branches 90 of the wire retainer when they are lifted, and there are three gripping-jaws pivoted above and suspended, which now swing downward, engage the wires of the respective branches, and gather them into the respective slots, 95 bending them over the cork and pressing them against a central abutment in the gripper-head. As soon as the branches are thus gathered and clamped fast the head rises a little and the holder in which the bottle is mounted 100 is rotated automatically, and this rotation twists the six wires forming the three branches

together on the top of the cork. The head now lifts still higher, and a cutter mounted on the face of the gripper-head sweeps around, nips and shears off the frayed end of the final 5 twist, bending the twist over to one side at the same time and down into the soft material of the cork. At this moment the bottle is released by the relieving of the clamps in the holder and the machine stops automatically 10 to receive another bottle. Thus one bottle is wired at each operation of the machine. I may say, however, that while the twist on the top of the cork is being trimmed, and after the branches have been lifted out 15 of the twisters, the wire-feeders operate to place a new set of wires, so that when the next bottle is placed in the holder by the attendant he will find the triangle of wires already formed.

20 The cams and other mechanisms which operate the devices named are placed, as herein shown, in the base of the machine and are driven from the power-shaft.

I will now proceed to describe the machine 25 more minutely with reference to the accompanying drawings, wherein—

Figure 1 is a side elevation, partly in section, of a machine for wiring bottles embodying my improvements. This view is taken 30 from the point indicated by the arrow y in Fig. 2. Fig. 1^a is a front view of the extreme upper part of the machine, omitted from Fig. 1 for lack of space. Fig. 2 is a sectional plan of the machine, taken in the plane indicated by the dotted line A A in Fig. 1. Fig. 3 is a side elevation of the mechanism in the base of the machine as seen from the point indicated by the arrow z in Fig. 2. This may be considered the front of the machine. Fig. 40 4 is a plan view of one of the wire feeding, cutting, and twisting mechanisms detached and on a large scale. This view also shows in dotted lines the relative positions of the other two twisters. Figs. 4^a, 4^b, and 4^c are 45 detached detail views of parts of the device illustrated in Fig. 4. Fig. 5 is a side view of the gears which operate the radial twisters detached and on the same scale as Fig. 4. Fig. 6 is a side elevation, partly broken away, 50 of the wire-feeder on the same scale as Fig. 4. Fig. 6^a is a view showing one of the feed-wheels and its gears detached. Fig. 7 is a plan view of the bottle-holder, showing the centering-clamp. Figs. 8 and 8^a are respectively 55 side views of the base and upper part of the bottle-holder. Fig. 9 is a side elevation of the gripper-head and grippers detached and on a larger scale than Fig. 1. Fig. 10 is an underside view of said gripper-head, 60 showing the trimmer for the top twist; and Fig. 10^a is a similar view showing the jaws of the trimmer in a position different from that seen in Fig. 10. Fig. 11 is an enlarged sectional view of a gripper-head and grippers 65 constructed according to my invention. This view is designed to illustrate more clearly the operation of this mechanism. Fig. 12 shows

the stoppered end of a bottle as it appears when wired by my machine.

1 represents the base-frame of the machine; 70 1^a, the upper bed arranged on the latter, and 1^b uprights, three in number, mounted on the base-frame 1. The uprights are connected at their upper ends by a frame 1^c. These constitute the fixed frame of the machine, and 75 it may have any form or construction most convenient or desirable. Within the frame and below the bed 1^a are arranged the several cam-shafts, cams, and driving mechanism.

2 is the main shaft, which may be driven 80 with a belt and pulley in the usual way, and an automatic stop mechanism may be employed to arrest the machine at the end of each wiring operation.

3 3^a 3^b are three radially-arranged cam-shafts, each provided with a set of cams for operating the respective like feeding and twisting mechanisms above. The cam-shaft 3 is driven from the main shaft 2 through the medium of a bevel-pinion 4 on the latter, gearing with a bevel-wheel 5 on the former. As herein shown, the main shaft makes four revolutions to one of the cam-shaft, and one revolution of the latter is necessary to a single wiring operation. The cam-shaft 3 drives the 90 other two cam-shafts 3^a through the medium of a bevel-wheel 6, which rotates loosely on a central shaft 7 in the base-frame.

The shaft 7 carries on its upper end a cross-head, to which are pivoted the two jaws 8 80 of the bottle clamp and holder. These jaws are provided at their upper ends each with a padded fork, so that when brought together the bottle is embraced between the forks. The jaws are drawn together on the bottle by 100 a spring, herein represented by a coil-spring 9, attached at its ends to the respective jaws. The jaws are provided with knuckles at their pivots to gear them together, and are opened by means of a treadle 10, coupled by a link 11 to a lever 12, which has a pin or projection engaging a circumferentially-grooved collar 13, which slides up and down on the shaft 7, and is coupled to the respective jaws by links 14. Springs 15 are arranged to retract the 110 collar 13, one end of said springs being secured to the collar and the other ends to the head of shaft 7. The spring 9 tends to retract said collar; but it is important that the collar should have some movement independent of that of the jaws for reasons to be explained, and hence the links 14 are slightly slotted.

The jaws 8 clamp on the body of the bottle, and there is a centering device and guide, 125 which embraces the bottle-neck just below the fillet. This device comprises the following mechanical features: Carried by a head 16^x on the shaft 7 is a frame comprising a curved plate 16, mounted on uprights 16^a. This plate 16 is at about the level of the fillet or the bottle to be wired. An upright rock-shaft 17 is mounted in the plate 16 and head 16^x and carries on its upper end a curved finger 18.

Two other like curved fingers 18^a are pivotally mounted on the plate 16, (see Figs. 7 and 8^a,) and arms on the latter-fingers are coupled by links 19 to the respective ends of a cross-bar 20, fixed on the upper end of the shaft 17. When this shaft is rocked in the proper direction, the several fingers 18 18^a 18^a are brought in toward the axis of the bottle-holder, and their tips press on the neck of the bottle just back of the fillet, and thus serve to center the bottle and steady it during the wiring operation.

The shaft 17 is rocked by means of the device comprising an oblique groove 13^b (see Fig. 8) in a block on the side of the splined sliding collar 13, a stud 13^a on a boss 17^a on the lower end of shaft 17 engaging said groove. Thus when the collar is drawn down by the operator the shaft 17 is rocked and the fingers 20 of the centering-clamp are opened, and when the operator removes the pressure from the treadle 10 and the springs 15 move the collar 13 up on the shaft 7 the stud 13^a rocks the shaft 17 in the other direction and closes the 25 centering-fingers on the bottle-neck. The slotted connection of the links 14 to the jaws 8 of the bottle-clamp allows of some variation in proportion between the bodies and necks of the bottles and provides a holder 30 adapted to clamp bottles having bodies of uniform size and necks varying in diameter, and also those having necks of uniform diameter and bodies varying in size. The centering-clamp is rendered variable by reason of the springs 15; but when the fingers of this 35 clamp have been set on the bottle-neck they cannot be spread apart by any ordinary force applied to themselves by reason of the stud and oblique slot device employed for converting the rectilineal motion of the collar 13 into 40 rotary motion of the shaft 17. This device introduces an inclined plane or wedge between said fingers and the collar, which is important, as it prevents any strain on the upper part of the bottle from pressing back the fingers. My holder combines thus a yielding and variable clamp for the body of the bottle and a non-yielding but variable clamp for the neck thereof, both clamps setting themselves 45 automatically.

Figs. 7, 8, and 8^a best illustrate the construction of the bottle-holding mechanism.

I will now describe the mechanism for feeding the wires and twisting them together upon 55 the bottle-neck, premising that there are three like sets of these mechanisms arranged to be actuated simultaneously, and a minute description of one will suffice for all. The wire is led from a spool or reel 21 (see Fig. 1) 60 of any kind through a wire guide and straightener 22, Figs. 4 and 6, which will be formed, by preference, of a series of horizontally and vertically arranged rollers to and between a pair of feed-rollers 23. These feed-rollers are 65 driven from a cam 24, which acts through a cam-rod 25^a and a pawl and ratchet 25 to impart intermittent rotation to a spur-wheel 26,

which gears with a pinion 27 on one of the feed-rollers 23. The rod 25^a is coupled at its lower end to a lever which rests on the cam, 70 and when the cam passes it descends of its own weight, drawing back the pawl. After passing the feed-rollers 23 (see Figs. 6 and 6^a) the wire passes through a cutter 29, (seen in dotted lines in Fig. 4,) which is adapted to sever it at the right moment. This cutter may be of any kind. Herein it consists of a plug which extends transversely across the path of the wire and has a transverse bore aligned with that along which the wire travels. By merely rocking the plug axially the wire is severed. This plug-cutter is rocked by means of a cam 30 and a rod 30^a. After passing the cutter the wire moves through the jaws of the radial twister, and thence 85 across and into the jaws of the twister next adjacent, the jaws being retracted and open. As represented in Fig. 4, the wire passes to that twister next adjacent at the right.

31^a and 31^b are the two jaws of the twister 90 31. These jaws are pivotally mounted on one end of a shaft 32, mounted rotatively in brackets 33 and 33^a, (see Figs. 4 and 4^b,) and is capable of some endwise movement in its bearing. On the other end of said shaft is a 95 long pinion 34, which gears with a spur-wheel 35, mounted on a stud on the frame. With the proportions here shown one-fourth of a rotation of the wheel 35 imparts two complete rotations to the pinion 34. The wheel 35 is 100 intermittently rotated by a cam 36 through the medium of a pawl-rod 37, a pawl 38, and a four-toothed ratchet-wheel 39 (see Fig. 5) on the wheel 35. Thus each time the cam 36 rotates it imparts two complete rotations to 105 the pinion 34 and the twister-shaft 32.

In Fig. 4 the axis of the bottle-holder is indicated by a small circle at x, and this axis will coincide with the axis of the bottle-neck when a bottle is in the holder. The wires from the three like feeders are fed so as to form the straight sides of a plane figure, in this case an equilateral triangle of which the point x is the center. The respective wires cross at the angles of the figure, and these 115 are situated in the respective twistlers, the intersection being in the axis of the twister and between the jaws of the same. Within each angle formed by the wires, which latter are represented by broken lines in Fig. 4, is a 120 stud 40 on the twister 31. The object of these studs is to hold the wires apart and distinct during the twisting.

I may say that where the wires form three sides of an equilateral triangle, as herein 125 shown, the axis of each wire-feeder will be at an angle of thirty degrees with the axis of the twister adjacent thereto.

When the twister is moved inward radially toward the point x, the jaws thereof close on 130 the wire, and when it is retracted they open. The longitudinal movement of the twister-shaft is effected by a cam 41 and a shifting-rod 42, the upper extremity of which is coupled

to a lever 42^a, which has a Y on its end, the branches of which engage a circumferential groove 43 in a collar fixed on the shaft 32. In a longitudinal slot in said shaft is mounted a 5 flat bar 44, on the end of which, within the hollow of the twister, is a double rack 44^a. This rack is clearly seen in Fig. 4^b, which is a sectional view showing the interior mechanism of the twister. The teeth on the double 10 rack gear with teeth on mutilated pinions 45 on or forming part of the respective twister-jaws 31^a and 31^b. Fig. 4^a is an edge view of the jaw 31^a with one of the pinions 45 attached. The rack is carried around with the 15 shaft 32, but does not move longitudinally with it. Hence from the engagement of the teeth of the rack with the pinions on the jaws the latter are caused to open and close by the endwise movement of the shaft which 20 carries them. The rack-bar 44 is prevented from moving endwise by being secured to a circumferentially-grooved collar 45^a, mounted loosely on the shaft 32, adjacent to the bearing-bracket 33, a pendent portion of said 25 bracket engaging the groove in said collar 45^a.

The end of the wire as it enters the twister from the rear passes under an overhanging portion on the back part of jaw 31^b, then crosses over obliquely and along the face of 30 jaw 31^a. To form a keeper for the wire, this jaw has an overhanging lip 31^ax. (Seen best in Fig. 4^c, which is an end view of the twister on a somewhat larger scale than Fig. 4.) There is also a pivoted keeper 32^a, mounted 35 in the twister 31 under the jaw 31^a, the inner upturned end of which is thrown up outside of the wire, so as to keep it in place next the jaw. When the jaws stand open, as in the drawings, the jaw 31^a stands over and 40 presses the outer end of the keeper 32^a, thus elevating its inner end; but as the jaw moves in in closing it moves off this extremity of the pivoted keeper, and the inner end thereof, which is the heavier, falls by gravity until 45 the lip thereon is below the wire, whereby the wire is set free. This device or some similar keeper is rendered desirable as a precautionary device to insure against the free end of the wire getting out of or away from the 50 jaw and out of line with the adjacent twister. In order that the wire coming from one twister may properly enter the jaws of that next adjacent, I prefer to cut away or flare the twister, as seen at 31^x in the several figures, so as to 55 facilitate its entrance. As the jaws of the twister come together on the wires, they clamp the latter just outside of or beyond the stud 40, and the two wires are engaged in a fork 31^c, (see Fig. 4^a), formed in a beak on the jaw 60 31^a, which laps over on the jaw 31^b. This beak is broken away in Fig. 4^c. At the moment the radial twisters move in and the jaws close on the wires the cutters 29 operate and sever the wires.

65 Fig. 4 represents the position of the feeders and radial twisters at the beginning of the wiring operation, the wires being already in

place about the axis of the bottle-holder. When the bottle shall have been placed and clamped, the machine is set in motion, the 70 twisters advance and close, the cutters sever the wires, and the twisters are rotated. This 75 twists down the three pairs of wires on the bottle-neck, forming a band thereabout, and leaving three branches therefrom in the twisters. These latter retract and open and instantly three lifters 46 are brought into play. This lifter is a lever of an L shape fulcrumed 80 at 47 and its operative arm 46^a arranged to play up and down in front of the twister and adjacent to the bottle-neck. The arm 46^a takes under the twisted branch of wire released by the twister, and by its upward movement bends the branch into a position parallel with the bottle-axis, or substantially so. 85 The lifter is held in its normal depressed position by a cam 48 and rod 49, and when the cam passes a spring 49^a acts to throw up the operative arm of the lifter. However, both 90 movements of the lifter may be effected by a cam or cams. When the branches of the wire band or retainer are lifted into an upright position by the lifters, they enter radially-arranged vertical slits 50 in a head 51, arranged in the prolongation of the bottle-axis and 95 above the bottle. This head 51 is fixed to a tubular stem 52, mounted to slide longitudinally in a bearing in the frame 1^c. (See Fig. 1.) In it is arranged a slide-rod 53, which is coupled at its lower inner end to a collar 54, 100 mounted to slide on the stem 52. The coupling of the collar and rod is effected by a stud 54^a, which plays in a slot of limited length in the tubular stem 52. A spring 55 between the collar 54 and head 51 tends by extension 105 to force the two apart and to keep the collar pressed upward as far as the slot will permit. On the head 51 are pivotally mounted three gripper-jaws 56, arranged to enter the respective slots and gather the three branches 110 in against the central abutment 51^a in the head. These grippers are actuated by the collar 54, to which they are coupled, respectively, by links 57. The spring 55 retracts the gripper-jaws by pushing the collar upward. 115 The resistance to compression of the spring 55 is such that when the slide-rod 53 is pushed down it carries the head 51 and its stem down with it until the head meets a resistance—as the cork in the bottle, for example—when the further movement downward of the rod and collar compresses the spring 55 and the jaws 56 of the gripper are made to clamp the branches of the retainer, as stated. The rod 53 is pushed or driven down by a cam 58 on 120 shaft 3, a rod 59, and a lever 60, mounted on the top of the machine-frame. This lever is coupled to the cam-rod 59 at one end and to the rod 53 at its other end. As the head 51 will be apt to meet with resistance at different levels, owing to the different sizes of bottles and different heights of their corks, provision is made for lost motion (the throw of the operating-cam being constant) by connecting the 125 130

lever 60 to the rod 53 by a pair of strong distending springs 61. The retraction of the rod 53 is effected by a spring-pawl 62 on the lever, which engages the teeth of a ratchet 5 on said rod, and as this pawl may, owing to the distention of the springs 61, engage the ratchet at different points, I provide a device for disengaging the pawl at a given point in its upward movement, no matter at what 10 point it may be engaged at the time with the ratchet on the bar. The pawl is provided with two lugs 63, which, as the lever carries the pawl upward, engage cam-faces on inclines 64 on a fixed upright 65, mounted on 15 the top of the machine-frame. As the lever 60 descends, the head 51 strikes the cork, and its further downward movement is arrested. Then the gripper-jaws clamp on the branches of the retainer, as described. At this moment 20 the lever 60 in its descent strikes and presses down a lever 66, mounted on the top of the machine-frame. To the short arm of this lever 66 is coupled a lifting-pawl 67, (seen in Fig. 1,) which is thus protruded in 25 an upward direction and made to engage a ratchet on the tubular stem 52, whereby said stem and its attached head, together with the gripper-jaws, are lifted a little and the pressure is taken off the cork. At this moment 30 the bottle-holder and, of course, the bottle clamped therein are rotated, and the three branches of the retainer twisted together on the top of the cork. The mechanism for effecting this rotation of the bottle-holder is best illustrated in Figs. 1 and 2. On the shaft 3 35 is a toothed wheel 68, which gears, through an intermediate 69, with a wheel 70. On the shaft of the wheel 70 is a bevel-pinion 71, which gears with a bevel-wheel 72 on a horizontal shaft, and on this shaft is ratcheted a 40 crank 73, which is coupled by a link to the free end of a lever 74. As the shaft 3 rotates, a stud 75, projecting from the back of wheel 5, (or it may be from a disk on shaft 3,) takes 45 under the lever 74 and raises it, thus turning the crank 73 partly round and through it imparting the proper number of complete rotations to the shaft 7 and the bottle-holder. In order to keep the bottle-holder steady during 50 the wiring operation, a suitable automatic lock may be provided. The twist having been formed on the top of the cork, the cam 58 passes, and a spring 59^a (see Fig. 1) throws up the lever 60 and lifts the gripper-head 51 high enough to permit the twist to be 55 trimmed. This trimmer is illustrated in Figs. 9, 10, and 10^a. A cam 76 on shaft 3 acts through a cam-rod 77 to rock an elbow-lever 78, to one arm of which is coupled a link 79. This link is coupled at its other end to a crank-arm 80 on a vertically-arranged rock-shaft 81, mounted at its lower end in a flange-bearing on the gripper-head 51 and at its upper end in a sliding bearing in the machine-frame. 65 On the lower end of this shaft is fixed an arm 82, which carries the fixed jaw 82^a of the trimmer. The movable jaw 82^b of the trimmer is

pivoted to the arm 82 and its tail is coupled to one end of a link 83, the other end of which is pivotally attached to the face of the head 70 51. (See Fig. 10.) When the arm swings over the lower face of the head, the movable jaw 82^b encounters the twist of the wire retainer and, actuated by the link 83, presses said twist up to the stationary jaw 82^a, and these 75 jaws then trim it off. Fig. 10^a shows the position of the jaws after they have closed on the twist. The further swing of the trimmer serves to bend over and flatten down the twist, and at this moment the cam 58 acts to depress 80 the gripper-head and with it the trimmer, and the pressure from the head serves to press the twist down on or into the soft material of the cork, as seen in Fig. 12, wherein 84 represents the bottle-neck, 85 the fillet thereon, 86 the 85 cork, 87 the wire band about the bottle-neck behind the fillet, 88 the branches of the retainer, and 89 the twist flattened down on the top of the cork.

It will be obvious to those skilled in the art 90 that by simply adding the necessary parts, duplicates of those shown, a retainer having four or more branches 88 may be applied, and it will also be obvious that the means last described for trimming the last twist and flattening it down might be omitted from the machine and these offices performed by hand or by another machine after the wired bottle is removed.

In Fig. 11, which is on a larger scale than 100 Fig. 9, I have shown a gripper-head 51 provided with four equally-spaced grippers 57, as this number of grippers is better adapted for illustration than three in a sectional elevation. It will be seen that the branches 105 88 of the retainer are engaged at the moment the twisting operation begins in the several slots 50 in the head, the lower face of which stands quite close to the cork 86. As the bottle rotates, the walls of these slots guide the 110 wires, and when the slack is taken up by the twist the wires of the branches slip under the grippers until at the finish they grasp only the extreme tips of the wires. The head 51 will by preference have a face-plate 90, as 115 seen in Fig. 11, not integral with the head.

Figs. 9 and 11 show only one spring 55 arranged within the hollow stem 52 and under the end of the slide-bar 53; but two or more of such springs may be employed, arranged 120 exteriorly in any convenient manner to effect the object sought.

As herein shown, the machine is so constructed that the bottle stands erect with its axis vertical, and some of the reciprocating 125 parts of the machine are represented as moved in one direction by cams and in the other direction by their own weight; but it is not essential that the machine be constructed in this way, the bottle need not stand upright, 130 and the parts referred to may be moved in both directions by cams.

I am aware that the details of construction embodied in the machine as herein shown

may be varied to a considerable extent without departing materially from my invention, and I do not, therefore, limit myself to these details.

5 Having thus described my invention, I claim—

1. In a machine for wiring bottles and the like, the combination, with a holder for the bottle, of feeding mechanism for placing the 10 strands of wire to form the sides of an angular plane figure about the axis of the bottle-holder, twisters radially arranged about said axis, one at each angle of said figure, said twisters being adapted to twist the adjacent 15 strands at each angle together in couples, thus forming the band and branches of the retainer, and the cutters for severing the wire, situated between the respective twisters and the wire-feeding mechanisms and operating after the 20 twisting thereof.

2. In a machine for wiring bottles and the like, the combination, with a centering-holder for the bottle-neck and three or more wire-feeders arranged about said holder and adapted 25 to feed the wires from one twister to that next adjacent, whereby the bottle-neck is embraced by substantially straight wires forming the sides of a plane figure, of the twisters, one adjacent to each feeder, said twisters being adapted to twist together the adjacent 30 wires at each angle in pairs to form the band and branches of the wire retainer, and cutters for severing the wires, situated between the respective twisters and the wire-feeding 35 mechanisms and operating after the twisting thereof.

3. In a machine for wiring bottles and the like, the combination, with a centering-holder for the neck of the bottle and the twisters 40 radially arranged about said holder, of the wire-feeders, one arranged at each twister and adapted to feed the wire from said twister into the twister next adjacent, whereby the several wires are crossed within the twisters 45 in pairs, as set forth, and the cutters for the wires arranged adjacent to and operating in connection with the feeders.

4. In a bottle-wiring machine, means for bending the branches of the retainer into position about the stoppered end of the bottle, 50 a gripper-head having radial slots to receive said branches, and a central abutment at the point of convergence of said slots, grippers adapted to play in said slots in the head and 55 to clamp the respective branches firmly against the central abutment, and means for actuating said grippers, all combined and arranged to operate substantially as set forth.

5. In a machine for wiring bottles and the like, the combination, to form the bottle-holder, of the shaft 7, the knuckled jaws 8, 60 mounted pivotally on the same, the spring which draws said jaws together, the sliding collar 13 on the shaft 7, a spring for sliding 65 said collar upward on the shaft, the links connecting said collar with the jaws 8, the rock-shaft 17, provided with a stud engaging an

oblique groove in the collar 13, the said stud, the finger 18 on the shaft 17, the fingers 18^a, mounted on the frame of the holder, the cross-bar 20 on the shaft 17, and the links coupling the respective ends of said cross-bar to the fingers 18^a, substantially as set forth. 70

6. In a machine for wiring bottles and the like, the combination, to form a twister, of a 75 rotatively-mounted shaft 32, capable of endwise movement in its bearings, the jaws pivotally mounted on said shaft, and provided each with a mutilated gear 45, the rack-bar 44, mounted in a longitudinal slot in said shaft, 80 means for rotating said shaft, and means for moving said shaft longitudinally independent of said rack-bar, whereby the jaws are closed by said endwise movement of the bar.

7. In a machine for wiring bottles and the like, the combination, with three radially-arranged twisters, of three wire-feeders, one adjacent to each twister, the axis of the feeder being at an angle to that of the twister and 85 said angle being such that the wire fed through 90 the twister intersects the axis of the twister between the jaws of the latter, substantially as set forth.

8. In a machine for wiring bottles and the like, the combination of three radially-arranged twisters placed at uniform distances apart about the axis of the bottle-holder, said bottle-holder, and three wire-feeders, one arranged adjacent to each twister, the axis of 95 the wire-feeder being at an angle of thirty 100 degrees with that of the adjacent twister, substantially as and for the purpose set forth.

9. As a means for imparting intermittent rotation to the bottle-holder, the combination, with the shaft 7, which carries said holder, 105 and the toothed wheel 68 on said shaft, of the rotatively-mounted toothed wheel 72 and its shaft, the train of wheels between the wheels 68 and 72, whereby the latter drives the former, a crank 73, ratcheted on the shaft 110 of the wheel 72, whereby each vibration of said crank imparts a rotary forward impulse to said wheel, a lever 74, pivoted to the frame at one end and coupled to said crank at the other end, and means, substantially as described, for imparting a vibrating movement to said lever at each wiring operation. 115

10. In a bottle-wiring machine, the combination, with an intermittently-rotating holder for the bottle and means for placing and 120 twisting the wires of the retainer about the neck of the bottle, of the slotted gripper-head arranged over the cork of the bottle and provided with a central abutment 51^a, the gripper-jaws pivotally mounted on said head and 125 adapted to enter the respective slots in the same, and means, substantially as set forth, for operating said jaws.

11. The combination, with the slotted gripper-head 51 and its stem 52, of the slide-bar 130 53, the compression-spring 55 between said slide-bar and head, whereby the bar may continue to descend after the head shall have met a resistance, the gripper-jaws 56, carried

by said head, and means whereby the said jaws are closed by the independent downward movement of said slide-bar, as set forth.

12. The combination, with the slotted gripper-head and its stem, the slide-bar 53, provided with a ratchet, and the compression-spring between said slide-bar and head, of the operating-lever 60, the springs 61, connecting said lever and the slide-bar, the pawl 62, carried by the lever and engaging the ratchet on the slide-bar, and means, substantially as described, for disengaging the said pawl when the lever rises, substantially as and for the purposes set forth.

13. The combination, with the gripper-head and its stem, the latter provided with a ratchet, the slide-bar, and the compression-spring between said head and slide-bar, of the lifting-lever 66, the pawl 67, carried by said lever, and the lever 60, which actuates the slide-bar, the lever 66 being in the path of the lever 60,

whereby when the latter descends it will strike the lever 66 and cause the pawl 67 to engage the stem of the gripper-head and lift the latter, substantially as and for the purpose set forth. 25

14. The combination, with the gripper-head, of the trimmer for the top twist mounted thereon, said trimmer comprising the vibrating arm 82, the fixed jaw 82^a on said arm, the movable jaw 82^b, pivoted on said arm, and the link 83, coupled to the tail of the movable jaw and pivotally attached to the head, substantially as set forth. 30

In witness whereof I have hereunto signed my name in the presence of two subscribing witnesses. 35

CHARLES L. CURTIS.
